(57) **CLAIM**

The ornamental design for a bracket, as shown and described.

DESCRIPTION

Cross-reference to related applications: U.S. patent application Ser. No. 29/222,363.

FIG. 1 is a realistic perspective view of a bracket, showing my new design;

FIG. 2 is a left view thereof;

FIG. 3 is a right view thereof;

FIG. 4 is a top view thereof;

FIG. 5 is a bottom view thereof;

FIG. 6 is a front view thereof; and,

FIG. 7 is a back view thereof.

My bracket is characterized by four legs, where three substantially orthogonal legs are threaded and are of substantially equal length and the longer fourth leg is threaded.
